(57) **CLAIM**

The ornamental design for a computing device, as shown and described.

DESCRIPTION

FIG. 1 is a front perspective view of a computing device showing our new design;

FIG. 2 is a front view thereof;

FIG. 3 is a rear view thereof;

FIG. 4 is a right side view thereof;

FIG. 5 is another right side view thereof, showing surrounded portion 9 shown in FIG. 9;

FIG. 6 is a left side view thereof;

FIG. 7 is a top view thereof;

FIG. 8 is a bottom view thereof; and,

FIG. 9 is an enlarged view thereof, taken from surrounded portion labeled as 9 in FIG. 5.

The even-length broken lines in the drawings illustrate portions of the computing device that form no part of the claimed design. The dash-dot-dash broken lines in FIGS. 5 and 9 are included to show a partially enlarged view only and form no part of the claimed design.
